UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ELECTRICAL RECEPTACLE.

1,355,301.

Specification of Letters Patent. Patented Oct. 12, 1920.

Application filed May 29, 1917. Serial No. 171,626.

To all whom it may concern:

Be it known that I, REUBEN B. BENJAMIN, a citizen of the United States, residing at Chicago, in the county of Cook and State of Illinois, have invented new and useful Improvements in Electrical Receptacles, of which the following is a full, clear, concise, and exact description, reference being had to the accompanying drawing, forming a part of this specification.

My invention relates to electrical receptacles.

One of the objects of my invention is to provide an improved electrical receptacle in which the leading-in wires are permanently secured to the terminals of the receptacle, which will be simple and compact in construction and cheap to manufacture. Further objects will appear from the detailed description to follow and from the appended claim.

In the drawings, in which one embodiment of my invention is shown—

Figure 1 is a side elevation of a receptacle embodying my invention;

Fig. 2 is an axial section on the line 2—2 of Fig. 3;

Fig. 3 is an axial section on the line 3—3 of Fig. 2;

Fig. 4 is a bottom view of Fig. 1;

Fig. 5 is a top view of Fig. 1;

Fig. 6 is a top view of Fig. 1 with the casing removed; and

Fig. 7 is a detail sectional view of a binding-terminal on the line 7—7 of Fig. 2.

Referring to the drawings in detail, the receptacle shown comprises a sheet-metal shell contact 10, a center contact 11, an insulating base 12 for supporting the shell and center contacts, and a sheet-metal casing 13 for housing the base 12 and associated parts. The insulating base 12 comprises a main circular body portion of substantially the same diameter as the shell contact 10 located within the shell contact and having a shoulder 14 for engagement with the inwardly-extending flange 15 of the shell contact 10. The base 12 is assembled with respect to the shell contact 10 by slipping it in place through the outer threaded portion 16 of the shell contact. The shell contact 10 and base 12 are held in assembled relation with respect to each other and to the casing 13 by means of a pair of hollow rivets 17

which extend through registering openings 55 in the base 12 and casing 13 and are riveted to the base and casing as indicated at 18 and 19. The upper outer end of these hollow rivets are closed, as indicated at 20, thus preventing foreign substances from getting into 60 the receptacle.

An insulating sleeve 21 of fiber or other suitable material is located between the shell contact 10 and the skirt portion 22 of the casing, and an insulating cap 23 is located 65 between the insulating base 12 and the cap portion 24 of the casing 13. The inwardly-extending flange 25 of the sleeve 21, the inwardly-extending flange 15 of the shell 10, and the outer edge 26 of the cap 23 are 70 clamped and held in place between the shoulder 14 of the insulating base and the cap portion 24 of the casing 13, by means of the securing rivets 17. An insulating sleeve 27 is provided for the neck portion 28 75 of the casing to prevent a short circuit in case the insulation on the leading-in wires 29 should become worn. The center contact 11 is secured to the insulating base 12 by means of a hollow rivet 30 which extends 80 through the registering openings in the contact 11 and insulating base 12. This rivet 30 is open at its upper end to receive the bared end of one of the leading-in wires 29, whereby this hollow rivet also serves as a binding-terminal. For connecting the other leading-in wire 29 to the shell contact, the shell contact is formed with a member 31 extending inwardly from the flange portion 15 and provided with upstanding ears 32 90 (Figs. 6 and 7) which are bent down over the bared end of the leading-in wire 29 to form an electrical connection. The bared ends of the leading-in wires 29 may be soldered to their respective binding-terminals, the rivet 30 serving as a soldering well 95 in making this connection.

In assembling the parts, the operation of riveting the rivets 17 to the casing 13 is the last operation to be performed, the wires 29 100 being first permanently connected to their respective binding terminals.

What I claim as new and desire to secure by Letters Patent of the United States is:

An electrical receptacle comprising a cup-shaped metal housing, a lining of sheet insulating material, fitting snugly inside said cup-shaped metal housing, a threaded shell

contact fitting snugly in said insulating lining, and an insulating base having an enlarged portion inside said threaded shell contact and a reduced portion extending beyond said threaded shell contact, a center contact supported by said base, said insulating base and cup-shaped metal housing having registering openings therein, a securing member extending through said openings parallel to the axis of said thread-

ed shell contact for securing said base, threaded shell contact and insulating lining in place in said housing, said reduced extending portion of said insulating base being recessed, and wiring terminals for the 15 feed wires for the receptacle contacts located in said recesses.

In witness whereof, I have hereunto subscribed my name.

REUBEN B. BENJAMIN.
